HEEL PLATE

Otho Davis, 214 Landsburg Drive,
Durham, N.C. 27707

Continuation-in-part of abandoned design application Ser.
No. 16,524, Apr. 1, 1969. This application Apr. 21,
1970, Ser. No. 22,548

Term of patent 14 years

Int. Cl. D2—04

U.S. Cl. D2—317

FIG. 1 is a front elevational view of a heel plate showing my new design,

FIG. 2 is a cross-sectional view taken along the line 2—2 of FIG. 4,

FIG. 3 is a side elevational view of the Heel Plate shown in FIG. 1,

FIG. 4 is a bottom plan view thereof,

FIG. 5 is a top plan view thereof,

This is a continuation-in-part of my copending application D. 16,524 filed Apr. 1, 1969 and now abandoned.

I claim:

The ornamental design for a heel plate, as shown and described.
